UNITED STATES PATENT OFFICE

2,372,072

FILAMENT STORAGE APPARATUS

John Flaws, Jr., East Cleveland, Ohio, assignor to
General Electric Company, a corporation of
New York

Original application November 16, 1938, Serial No.
240,779. Divided and this application March
12, 1942, Serial No. 434,451

5 Claims. (Cl. 206—56)

My invention relates in general to method and apparatus for storing and transporting coiled filaments for electric lamps and the like. The present application is a division of my copending application, Serial No. 240,779, filed November 16, 1938, and assigned to the assignee of the present application. The copending application has matured into Patent 2,280,573.

The usual process of handling coiled lamp filaments heretofore consisted in placing small quantities thereof in closed containers, following inspection of the filaments, and then transporting the containers to a place where the filaments are to be assembled with the other lamp parts. The filaments are manually removed from the container to small piles either on automatic mounting apparatus or on trays from which they are taken manually and mounted. Both steps of this process are objectionable, the disposition of the filaments in the closed container causing the filaments to rub on each other and the coils thereof to interlock, and the subsequent separation of the filaments, at the point of assembly with the other lamp parts, being rendered difficult by reason of the relatively small size and tangled condition of the filaments.

To avoid these objections, therefore, one object of my invention is to provide a method and apparatus for storing coiled filaments in individually separated condition.

Another object of my invention is to provide a convenient magazine for storing and transferring a relatively large quantity of coiled filaments in individually separated relation to the point of use, and which allows the release of said filaments at definite and regular intervals.

Further objects and advantages of my invention will appear from the following description of a species thereof and from the accompanying drawing, in which:

Fig. 1 is a perspective view of apparatus comprising my invention for storing coiled filaments in individually separated relation in a magazine according to the invention; Fig. 2 is a fragmentary sectional view of the magazine or storage device comprising my invention; Fig. 3 is a transverse sectional view of the storage magazine comprising my invention; and Fig. 4 is a fragmentary perspective view, on an enlarged scale, of an end portion of the loading strip of the magazine shown in Figs. 2 and 3.

Referring to the drawing, the apparatus according to the invention for storing coiled filaments 10 in individually spaced relation comprises a sorting and inspection table 11 having

a glass plate 12 on which the filaments 10 to be stored are disposed for visual examination thereof by an operator seated before the table. To facilitate inspection of the filaments, suitable light projecting means (not shown) may be employed for the purpose of providing adequate illumination on the top and bottom of the glass plate 12. In addition, the table 11 may be further provided with optical means for projecting an enlarged image of the particular filament 10 under examination onto a screen located adjacent the table.

The filaments 10, as they pass inspection, are inserted in a storage device or magazine 13 comprising a reel or spool 14 on which is wound a flexible loading strip 15 provided, at closely spaced regular intervals therealong, with small laterally extending elongated recesses or indentations 16 terminating short of the side edges of the strip and of the proper size and shape to each receive one of the filaments 10. The flexible strip 15 may be formed or molded of any suitable material, such as metal, rubber or paper, possessing the flexibility necessary to permit winding of the strip onto the spool 14. Preferably, however, the loading strip 15 is made of a relatively thin strip of stainless steel having the pockets 16 punched or pressed therein. Substantially the entire length of the loading strip 15 is preferably provided with the recesses or pockets 16 to thereby permit maximum utilization of the length of the strip for filament storage purposes. However, the pockets 16, for a limited distance back from each end of the loading strip 15, are preferably partially filled with solder (as indicated at 19 in Fig. 4) to prevent the insertion of filaments in such end pockets, the solder filling only the opposite ends of each pocket 16. The end sections of the loading strip so provided with the solder-filled recesses or pockets thus constitute, in effect, leader strip portions 17 which serve to overlap and seal the last turn of the filament-containing intermediate portions of the loading strip, when the strip is wound on the spool 14, so as to prevent the filaments carried by such last turn of the loading strip from dropping out of the pockets in which they are disposed.

The unloaded magazine 13 is positioned at the right-hand side of the table 11 and is fixedly mounted on a rearwardly extending shaft 18 with the loading strip 15 of the magazine in alignment with a track or channel 19 extending along the front or forward edge of the table 11. The said track 19 is formed in a bar 20 secured to the table 11 and extending along the front edge thereof. The empty loading strip 15 is unwound from the

spool 14 of the storage magazine and is moved, with the pockets 16 thereof facing upwardly, along the track 19 by means of a grooved feeding drum or roller 21 which is shaped to engage the pockets 16 in the loading strip 15 and which is driven from a suitable source not shown but diagrammatically represented by the electric motor 22. The feed roller 21 is fixedly mounted on a rearwardly extending shaft 23 supported by brackets 24, 25 on the upper surface of the table 11. The feed roller 21 and shaft 23 are driven from a shaft 26, extending across the rear of the table 11 below the level of the top thereof, through a set of lower intermeshing gears 27, 28, a vertical shaft 29, and a set of upper intermeshing gears 30, 31. The motor 22 may, for instance, be connected to shaft 26 by a suitable speed reducer (not shown).

The loading strip 15 is pulled or unwound from the supply spool 14 by the rotation of the feeding roller 21. The unwinding of the strip 15 from the spool 14 causes the latter, as well as the shaft 18 on which it is fixedly mounted, to turn or rotate against the resistance of a brake (not shown) engaging the said shaft 18. The supply spool 14 is retained on the shaft 18 by means of a knob or retaining nut 32 threaded onto the front end of said shaft.

The loading strip 15 is maintained in engagement with the feed roller 21 by means of a co-operating grooved idling roller or drum 33 rotatably mounted on a stud 34 extending from the bar 20 on the table 11. That portion of the loading strip 15 adjacent the feed roller 21 and disposed in the track 19 is directly in the line of movement of the operator's right hand and forearm and is protected therefrom by a plate 35 which also serves as a rest for the operator's forearm.

To start the filament loading operation, the free end or leader portion 17 of the loading strip 15 is inserted between the feed rollers 21, 33, then drawn through the track 19 and suitably fastened to the core of a take-up spool or reel 36 located adjacent the terminal or left-hand end of the track 19 and in alignment therewith. The said take-up spool 36 is fixedly mounted on the front end of a rearwardly extending shaft 37 supported by a bracket 38 extending from the table 11. To keep that portion of the loading strip 15 between the feeding roller 21 and the take-up spool 36 tightly stretched at all times, the take-up spool is turned or rotated by the shaft 37 with sufficient force to so maintain the strip 15 taut, the take-up spool preferably being rotated in a direction (counter-clockwise with the arrangement shown in Fig. 1) such that the loading strip 15 is wound on the said spool 36 with the pockets 16 in the strip facing outwardly. The shaft 37 is turned with the necessary force to keep the proper tension in the loading strip 15 by the frictional engagement of a drum 39, fixedly mounted on the shaft 37, with a surrounding band 40 carried by a disc 41 rotatably mounted on the shaft 37. One end of the band 40 is fastened to the disc 41 by a stud 42 while the other end is connected to the said stud through a coiled tension spring 43 which tends to contract and draw the band 40 tightly about the periphery of the drum 39. The disc 41 is driven through a bevel gear 44 which rotates as a unit with the said disc 41 and which meshes with a bevel gear 45 on the drive shaft 26.

Following the inspection thereof, the filaments 10 are separated by the operator and either lifted or slid into the pockets 16 in the loading strip 15 which is moved or indexed along the track 19 at

a uniform rate from right to left at such a speed as to present empty pockets 16 to the filament loading position as and when they are required. After passing the loading position, the loading strip 15 moves underneath a sealing strip 46 which is fed to the loading strip so as to overlie the top thereof and retain or seal the filaments 10 in the pockets 16 of said strip 15. The sealing strip 46 is preferably made from a material not likely to leave threads or other contamination on the filaments 10 in the pockets 16, such as, for instance, the transparent material manufactured under the trade name "Cellophane" by the E. I. Du Pont de Nemours & Co., of Wilmington, Delaware. However, if desired, the sealing strip 46 can be dispensed with providing the lower surface of the loading strip 15 is so formed as to seal or cover the pockets 16 in the underlying turn of the loading strip when the latter is wound tightly on the take-up spool 36, and providing, further, that some suitable means are employed to temporarily retain the filaments in the pockets 16, as the strip 15 passes around the take-up spool, until the said pockets are covered or overlapped by the overlying turn of the loading strip.

The sealing strip 46 is fed to the loading strip 15 from a supply spool 47 which is rotatably mounted on a shaft 48 extending from a bracket 49 attached to the table 11. The sealing strip 46 is wound together with the loading strip 15 onto the take-up spool 36, and is pulled from the supply spool 47 against the resistance of a brake (not shown) which engages the bracket 49 and the shaft 48 on which the spool 47 is mounted. The sealing strip 46 is guided onto the upper surface of the loading strip 15 by a guide roller 50 around and under which the sealing strip passes, the said guide roller being located adjacent the terminal end of the track 19 and being rotatably mounted on a pin 51 carried by the bar 20. An elongated weight 52, pivotally mounted at one end on the pin 51 and extending to a point beyond the center of the take-up spool shaft 37, rests on top the sealing strip 46 so as to press and maintain the sealing strip against the loading strip 15, on the way to the take-up spool, and thereby prevent the escape of the filaments 10 from the pockets 16 in the loading strip during such travel.

To insure the proper loading of each pocket 16 in the loading strip with a filament 10, suitable indicating or control means 53 are provided for interrupting the movement of the loading strip 15 along the track 19 when an improperly loaded pocket 16 is encountered. In this way, the operator is apprised of the improper loading of the strip 15 and can therefore correct such condition so that the loading strip 15 will afterwards function properly in the feeding apparatus of a filament mounting machine; also, so that a definite number of filaments 10 will be known to occupy a previously counted and marked number of pockets 16.

The indicator means 53 referred to above comprises a movable finger 54 disposed above the loading strip 15 at a point beyond the loading position thereof and adapted to enter the pockets 16 and engage the filaments 10 therein as the loading strip 15 moves along the track 19. The said finger 54 is mounted on one end of an arm 55 the other end of which is pivoted on a pin 56 in a bracket 57. The said bracket is fastened to the bar 20, and bridges the track 19 in which the loading strip 15 is located. The finger 54 is carried into engagement with the loading strip

15 and the filaments 10 in the pockets 16 thereof by the weight of the arm 55.

When more than one filament 10 in any one pocket 16 is encountered by the finger 54, the said finger and its associated arm 55 are raised above their normal position. Such a raising of the arm 55 brings a contact 58, carried by the arm 55, into engagement with a co-operating stationary contact 59 mounted on the bar 20, thus completing a circuit through the secondary 61 of a transformer 60 (the primary 62 of which is connected to a source of current) and through the coil 64 of a relay 63. The completion of the said circuit through the coil 64 results in the energization of said coil which then draws the movable armature 65 of the relay out of engagement with its co-operating stationary contact 66, thus interrupting the current supply circuit to the electric motor 22. The de-energization of the motor 22 then interrupts the operation of the feeding mechanism for the loading strip 15 so that movement of said strip along the track 19 is temporarily stopped while the operator corrects the improper loading condition of the particular pocket 16 in the loading strip. After such correction, normal operation of the apparatus is then resumed.

When an empty pocket 16 is encountered by the control finger 54, the arm 55 moves to a position lower than normal, causing a second contact (not shown) on said arm to engage another stationary contact (also not shown) mounted on the bar 20. These contacts are likewise connected to the transformer secondary 61 and the relay coil 64 in the same manner as contacts 58, 59 so that their interengagement completes the circuit through the relay coil 64 which then interrupts operation of the electric motor 22 and therefore movement of the loading strip 15 along the track 19, the same as when more than one filament 10 is disposed within a single pocket 16.

After completion of the filament loading of the strip 15, the tail end or rear leader portion of said strip is manually wound on the take-up spool 36 and held in a tightly coiled condition thereon until the said end of the strip is suitably secured against unwinding. Any convenient means, such as a paper sticker, can be used to hold the tail end of the loading strip 15 in its tightly coiled condition on the take-up spool 36. After such fastening of the tail end of the loading strip, the spool 36, on which said strip is mounted, is then removed from the shaft 37 and either stored or transferred to the place where the filaments 10 contained in said spool are to be used. Since the filaments 10 are contained within sealed chambers or pockets, the possibility of contamination thereof and injury thereto during storage and shipping is completely eliminated.

The structure of the spools 14 and 36 of the filament storage magazine 13 comprising my invention is preferably made alike so as to permit interchangeability of said spools in the loading and unloading apparatus therefor. As shown in Fig. 3, each spool 14, 36 comprises a pair of flanges 67, 68 one of which (68) is slidably mounted on an outer reduced diameter portion 69 of a hub 70 extending from the inner face of the other flange 67, the inner enlarged portion of said hub forming the core of the spool. The movable flange 68 is secured in place on the reduced hub portion 69 of the other flange 67 by means of a retaining nut 71 threaded into the hub 70 and provided with a flange 72 which engages the movable flange 68. The inner faces

of the flanges 67, 68 are preferably provided with resilient facings 73, 73 which may be made of, for instance, rubber and against which the loading strip 15 of the magazine normally bears.

During the periods the loading strip 15 is being removed from or wound onto the spool 14 or 36, the flanges 67, 68 thereof are slightly separated so as to provide a small amount of clearance between the edges of the loading strip 15 and the resilient inner facing 73 of the spool, the said clearance thus permitting free movement of the loading strip between the spool flanges. However, after the loading strip 15 has been wound onto the spool, and during the period when the magazine is held in storage or is being shipped, the resilient facings 73 of the flanges 67, 68 are forced against the side edges of the loading strip 15. This movement of the flanges 67, 68 is controlled by the extent to which the retaining nut 71 is screwed into the hub 70 and also by a plurality of spring-pressed plungers or pins 74 (only one of which is shown in Fig. 3) which are mounted in the enlarged portion of the hub 70 and which are pressed into engagement with co-operating depressions or recesses 75 in the inner face of the flange 68 by the expansion of coil springs 76 surrounding the said plungers 74. The springs 76 are located in wells 77 in the hub 70 and butt at one end against the bottom walls of said wells and at the other end against heads 78 on said plungers, the said heads 78 fitting into the co-operating apertures or recesses 75 in the movable flange 68. The pressure of the pins or plungers 74 against the movable flange 68 of the spool causes it to move outwardly when the retaining nut 71 is unscrewed from the hub 70, while the presence of the heads 78 of said pins in the recesses 75 of said movable flange 68 causes both flanges 67, 68 to rotate together as a unit.

Although the resilient facings 73 on the flanges 67, 68 seal the edges of both the loading strip 15 and the sealing strip 46 so that all moisture, lint and other foreign substance may not reach the filaments 10 in the pockets 16, it is not always necessary to provide such resilient facings inasmuch as the edge portions of the loading strip 15 and the sealing strip 46, when the said strips are wound tightly on a spool, are drawn tightly together and seal the pockets 16 very effectively. Where the sealing of the pockets 16 is so effected by the tight winding together of the loading and sealing strips 15, 46, then the spools 14, 36, if desired, may be permanently attached to the loading apparatus and the loading strip 15 conveniently wound on a hollow core (such as shown for the sealing strip in Fig. 1) which can be slid on and off the spools with the loading and sealing strips 15, 46 tightly wound in place thereon. Even with such an arrangement, the filaments 10 are nevertheless sealed and retained in separate pockets or chambers, which therefore prevents their contamination; also, the loaded magazine can be shipped and stored with safety, although somewhat more care is required in handling to prevent injury to the loading strip 15 and to prevent the unwinding thereof.

In the appended claims, the expression "flexible strip means" is intended to include either the loading strip 15 alone or in combination with the separate sealing strip 46.

What I claim as new and desire to secure by Letters Patent of the United States is:

1. A storage device for a plurality of helically coiled filaments for electric lamps comprising a flexible strip provided with a plurality of elon-

gated pockets for accommodating the said coiled filaments in individually separated relation therein, the said pockets being formed by depressions in the strip material confined wholly within the boundaries of the strip and sufficiently deep to wholly enclose the filaments.

2. A storage device for a plurality of helically coiled filaments for electric lamps comprising a flexible strip provided with a plurality of transversely extending elongated pockets for accommodating the said coiled filaments in individually separated relation therein, the said pockets being formed by depressions in the strip material confined wholly within the boundaries of the strip and sufficiently deep to wholly enclose the filaments.

3. A storage device for a plurality of helically coiled filaments for electric lamps comprising a spool, and flexible strip means spirally wound onto said spool and provided with a plurality of elongated pockets for accommodating the said coiled filaments in individually separated relation therein, the said pockets being formed by depressions in the strip material confined wholly within the boundaries of the strip and sufficiently deep to wholly enclose the filaments, said strip means also having retaining means at least partially cover-

ing said pockets for retaining the coiled filaments therein.

4. A storage device for a plurality of helically coiled filaments for electric lamps comprising a spool, a flexible loading strip wound onto said spool and provided with a plurality of pockets for accommodating the said coiled filaments in individually separated relation therein, the said pockets being formed by depressions in the strip material confined wholly within the boundaries of the strip and sufficiently deep to wholly enclose the filaments, and a flexible sealing strip wound together with said loading strip onto said spool and covering the said pockets in said loading strip so as to retain the coiled filaments in said pockets.

5. A storage device for helically coiled filaments for electric lamps comprising a spool including a hub portion and relatively separable flanges on said hub portion, said flanges having inner faces of resilient material, and a flexible strip spirally wound on said spool between its flanges, said strip being provided with pockets for accommodating the filaments in individually separated relation, and means for drawing the spool flanges together to compress their resilient inner faces against the edges of the coiled strip.

JOHN FLAWS, JR.
